[57] CLAIM

The ornamental design of a trailer mounted barbecue and beverage dispenser, as shown.

DESCRIPTION

FIG. 1 is a perspective view of a trailer mounted barbecue and beverage dispenser showing my new design; FIG. 2 is a side elevational view thereof; FIG. 3 is a front elevational view thereof; FIG. 4 is a side elevational view of the opposite side of FIG. 2; FIG. 5 is a rear elevational view thereof; and, FIG. 6 is a top plan view thereof. The undisclosed bottom is plain and unornamented.
